UNITED STATES PATENT OFFICE.

LYLE J. HICKS, OF DETROIT, MICHIGAN.

COMBINED CASING AND SUPPORTING BRACKET.

Application filed July 14, 1922. Serial No. 575,023.

This invention relates to receptacle supports and the object of the invention is to provide a receptacle support adapted to space the receptacle from the part on which it is mounted and to lock a receptacle of two parts together. A further object of the invention is to provide a receptacle support of the character described having a shoulder adapted to support the base of the receptacle, such as a two part receptacle case or the like, in spaced relation with the part on which the support is secured and having a tongue portion extending upwardly through the base and cover of the receptacle, the upper end of the tongue portion being bent over to lock the base and cover of the receptacle between the supporting shoulders and said bent over portion. A further object of the invention is to provide a receptacle support for each end of a receptacle, the supports being provided with an apertured base having a large aperture opening into a smaller aperture, the large aperture being adapted to be placed over the head of a nail, screw or the like at which time the receptacle may be given a slight turn to position the smaller portions of the apertures beneath the said heads and bindingly lock the device in the supported position. A further object of the invention is to provide a receptacle support which may be cheaply made and which may be formed with a single stamping of sheet metal or the like. These objects and the several novel features of the invention are hereinafter more fully described and claimed and the preferred form of construction by which these objects are attained is shown in the accompanying drawings in which—

Fig. 1 is a side elevation of a receptacle provided with supports embodying my invention, the receptacle shown being a two part transformer case.

Fig. 2 is a plan view of the supports, the receptacle being shown in dotted lines.

Fig. 3 is a perspective view of the receptacle support.

As shown in Fig. 3 the receptacle support consists of a base 1 preferably formed of sheet metal and having an aperture 2 therein into which a smaller aperture 3 opens. Extending upwardly at approximately a right angle from the base 1 is a portion 4 which is provided with inwardly bent shoulders 5 curved to fit the end of the receptacle which is here shown as a two-part transfor-

mer case as indicated in Fig. 1. The portion 4 is provided with a central extending portion or tongue 6 which is bent to form a shoulder 7 as shown in Fig. 3, which also forms a support for the base portion 8 of the transformer case. This portion or tongue 6 extends upwardly through apertures provided in the base 8 and cover 9 of the transformer case and the upper end 10 of the tongue 6 is then bent over as shown in Fig. 1 to lock the base and cover of the transformer case together between the shoulders 5 and the bent portion 10. To support the device a pair of nails or screws 11 may be driven into the member on which the device is to be mounted, the nails or screws being spaced apart to conform with the space between the apertures 3 on the opposite sides of Fig. 2, it being necessary that the heads 12 of the nails or screws be smaller than the apertures 2 and larger than the apertures 3. When the nails or screws have been driven down into the member to considerable extent the apertures 2 are positioned over the heads thereof at which time the receptacle may be turned to bring the apertures 3 beneath the heads 12 of the nails or screws. If desired the nails or screws may be driven down tight at this time which locks the receptacle supports to the member on which they are mounted. While I have shown a two-part transformer case it is to be understood that the supports are not limited to use with this type of receptacle but may be used with any type of two-part receptacle in which the supports are to be used to support the receptacle in spaced relation with the member on which it is mounted and at the same time lock the two parts of the receptacle together.

From the foregoing description it becomes evident that the device is very simple and efficient in operation, of very low manufacturing cost, is easily made and provides a device which accomplishes the objects desired.

Having thus fully described my invention, its utility and mode of operation, what I claim and desire to secure by Letters Patent of the United States is—

A supporting bracket for an article formed of more than one part having aligned apertures at opposite ends consisting of a metal member having a body, a tongue extending outwardly therefrom centrally of the said body at one end and of less width

than the body, an integral lug on each side of the said tongue extending at a right angle to the body, and a foot portion at the opposite end of the body extending at practically a right angle thereto and having an aperture consisting of an elongated slot opening to an enlargement at one end to fit over a headed screw or the like, said

tongue being adapted for insertion through the aligned apertures of the casing parts, the terminal portion bent thereover securing the same between the lugs and the said bent end in spaced relation with the foot portions. In testimony whereof, I sign this specification.

LYLE J. HICKS.
